(57) **CLAIM**

The ornamental design for a front panel for reverse vending machine, as shown and described.

DESCRIPTION

FIG. 1 is a perspective view of a front panel for reverse vending machine of the claimed design;

FIG. 2 is a front view of the front panel for reverse vending machine of the claimed design;

FIG. 3 is a right side view of the front panel for reverse vending machine of the claimed design;

FIG. 4 is a left side view of the front panel for reverse vending machine of the claimed design;

FIG. 5 is a top view of the front panel for reverse vending machine of the claimed design;

FIG. 6 is a bottom view of the front panel for reverse vending machine of the claimed design; and,

FIG. 7 is a rear view of the front panel for reverse vending machine of the claimed design.

The broken line portion of the figure drawings is included to show environmental structure that form no part of the claimed design.
